(57) **CLAIM**

The ornamental design for a light fixture, as shown and
described.

DESCRIPTION

FIG. 1 is a perspective view of a light fixture in accordance
with my design;

FIG. 2 is a front elevation view of the light fixture in accordance
with my design;

FIG. 3 is a back elevation view of the light fixture in accordance
with my design;

FIG. 4 is a bottom plan view of the light fixture in accordance
with my design;

FIG. 5 is a top plan view of the light fixture in accordance with
my design;

FIG. 6 is a side elevation view of the light fixture in accordance
with my design taken along the lines 6—6 of FIG. 3;
and,

FIG. 7 is an opposite side elevation view of the light fixture in
accordance with my design taken along the lines 7—7 of FIG.
3.

The broken-line disclosure of elements is understood to represent
portions of the article in which the design is embodied,
but which form no part of the claimed design.

The portion of the light fixture shown broken away in FIGS.
1-5 to depict indeterminate length.
